(57) **CLAIM**

The ornamental design for ballistic vest, as shown and described.

DESCRIPTION

FIG. 1 is a perspective view showing our new design; FIG. 2 is a front elevational view;

FIG. 3 is a side elevational view taken from the right side of FIG. 1, the opposite side of the ballistic vest being a mirror image of the view shown in FIG. 3;

FIG. 4 is a back elevational view; and,

FIG. 5 is a top view of the design.

The following fragmentary patterns shown in the drawing are repeated uniformly throughout the segments of the vest in which they are shown: the criss-cross pattern is understood to represent nylon fabric, the pattern of circles is understood to represent perforated fabric, and the grey-tone pattern is understood to represent the loop structure of a hook-and-loop fastener. The broken lines in the drawing are understood to represent stitching.

1 Claim, 5 Drawing Sheets
